CLAIM

The ornamental design for a toy track section, as shown and described.

DESCRIPTION

FIG. 1 is a front, top, right-side perspective view of a toy track section;
FIG. 2 is a front view thereof;
FIG. 3 is a rear view thereof;
FIG. 4 is a top view thereof;
FIG. 5 is a bottom view thereof.
FIG. 6 is a right-side view thereof; and,
FIG. 7 is a left-side view thereof.

(Continued)

The broken lines in the drawings depict portions of the toy track section that form no part of the claimed design.

1 Claim, 4 Drawing Sheets
